US0D1043348S

(12) **United States Design Patent** (10) Patent No.: **US D1,043,348 S**
(45) Date of Patent: ** Sep. 24, 2024

(54) **BOTTLE**(71) Applicant: **H.J. Heinz Company Brands LLC**,
Pittsburgh, PA (US)(72) Inventors: **Michelle Marie Hayden**, San
Francisco, CA (US); **Peter Brian**
Clarke, Newton, CT (US); **James E.**
McCay, Fairfield, CT (US); **Sean**
Evelich, Hamden, CT (US); **Trond**
Erik Tollefson, London (GB)(73) Assignee: **H.J. Heinz Company Brands LLC**,
Pittsburgh, PA (US)(**) Term: **15 Years**(21) Appl. No.: **29/809,075**(22) Filed: **Sep. 24, 2021**(51) LOC (14) Cl. **07-01**

(52) U.S. Cl.

USPC ..... **D9/530**; D9/550; D9/558(58) **Field of Classification Search**USPC D9/530, 531, 558, 574, 529, 537, 539,

CLAIM

The ornamental design for a bottle, as shown and described.

DESCRIPTION

FIG. 1 is a top, front perspective view of a bottle in accordance with a first embodiment of our new design;
FIG. 2 is a bottom, rear perspective view thereof;
FIG. 3 is a front elevation view thereof;
FIG. 4 is a rear elevation view thereof;

FIG. 5 is a right side elevation view thereof;
FIG. 6 is a left side elevation view thereof;
FIG. 7 is a top plan view thereof;
FIG. 8 is a bottom plan view thereof;
FIG. 9 is a top, front perspective view of a bottle in accordance with a second embodiment of our new design;
FIG. 10 is a bottom, rear perspective view thereof;
FIG. 11 is a front elevation view thereof;
FIG. 12 is a rear elevation view thereof;
FIG. 13 is a right side elevation view thereof;
FIG. 14 is a left side elevation view thereof;
FIG. 15 is a top plan view thereof;
FIG. 16 is a bottom plan view thereof;
FIG. 17 is a top, front perspective view of a bottle in accordance with a third embodiment of our new design;
FIG. 18 is a bottom, rear perspective view thereof;
FIG. 19 is a front elevation view thereof;
FIG. 20 is a rear elevation view thereof;
FIG. 21 is a right side elevation view thereof;
FIG. 22 is a left side elevation view thereof;
FIG. 23 is a top plan view thereof; and,
FIG. 24 is a bottom plan view thereof.

The broken lines shown illustrate portions of the bottle and form no part of the claimed design. The dash-dot lines represent the bounds of the claim and form no part of the claimed design.
